UNITED STATES PATENT OFFICE.

HARRY LATZ, OF MOUNT ARLINGTON, NEW JERSEY.

GAME MARKER.

Application filed July 6, 1922. Serial No. 573,095.

To all whom it may concern:

Be it known that I, HARRY LATZ, a citizen of the United States of America, and a resident of Mount Arlington, county of Sussex, State of New Jersey, have invented certain new and useful Improvements in Game Markers, of which the following is a specification.

My invention relates to game markers, and more particularly to mammoth checker-pieces designed especially for use in playing games of checkers or the like on a board of relatively large dimensions, such as illustrated in the patent to Wallstein, No. 877,814, of January 28, 1908, and has for its object to provide an improved and novel marker or piece capable of being manipulated with a minimum of effort and constructed in a manner to permit several of the markers to be superimposed upon each other in the playing of the game. My invention will be fully described hereinafter and the features of novelty will be pointed out in the appended claims.

In the accompanying drawings, which illustrate an example of the invention without defining its limits, Fig. 1 is a face view, on a small scale, of an example of the gameboard; Fig. 2 is a plan view of a marker constructed in accordance with my invention; Fig. 3 is a cross-section thereof on the line 3—3 of Fig. 2; Fig. 4 is a sectional view showing two of the markers superimposed upon each other, and Fig. 5 is a perspective view illustrating one way of manipulating the markers.

The marker is intended primarily for playing checkers or similar games upon boards of large dimensions designed for use, for instance, in the open air upon the lawn, and in such case termed lawn-checkers, or in other places where the game upon a mammoth scale may be played; in the playing of the game on boards of the indicated type, it is necessary, because of the dimensions of the board and the inaccessibility of parts thereof, to manipulate the markers or pieces by means of suitable devices, such as sticks or rods of convenient length and provided at one end, for instance, with hooks or equivalent devices adapted to be engaged with the markers. In the playing of the game of checkers, it further becomes necessary, during the progress of the playing, to superimpose one marker or piece upon another to

designate what is termed a "king" when the latter has been secured by a player.

My improved marker or piece is especially designed to meet the requirements outlined above and comprises a suitably shaped member 5 constructed of suitable material, preferably in the form of a disk, and provided at its centre with an aperture 6. A loop 7 of wire or other material extends diametrically across the aperture 6 and projects therethrough and beyond the surface of the member 5 in one direction, preferably in converging form and terminating in an apex 8 as shown in Figs. 4 and 5, it being understood that the loop 7 is permanently connected with the marker 5 in any convenient manner.

By projecting the loop 7 beyond the surface of the marker 5, as indicated in Figs. 3 and 5, the apex 8 thereof is in a readily accessible position to accommodate a lifting implement and is easily engaged, for instance, by the hook or other device 9 at the end of the stick or rod 10, whereby the markers are manipulated. Furthermore, by construction the loop 7 of converging form, it is easily possible to place one marker upon the other, in which case the loop 7 of the lowermost marker projects through and beyond the aperture 6 of the uppermost marker as shown in Fig. 4 and thus permits both to be simultaneously lifted by engaging the hook or other device 9 with the loop 7 of the lowermost marker. The arrangement and dimensions of the parts is such that when thus placed one upon the other, the uppermost marker lies in flat surface engagement with the lowermost marker with the apertures 6 of both in registry with each other as illustrated in Fig. 4. These apertures further provide means whereby the manipulation of the markers to different positions upon the board is facilitated; that is to say, the hook or other device 9 at the end of the rod or stick 10 whereby said markers may be manipulated may be engaged with the periphery of the aperture 6 when it is desired to either pull or push the marker to a different position upon the board or to adjust said marker to a proper position upon one of the squares upon said board. This action is possible with individual markers and also with a pair of markers placed one upon the other as shown in Fig. 4 to constitute a king. The

markers are differently colored in sets in the customary manner and may be utilized to play games of checkers or the like upon boards of mammoth size located either in doors, as for instance upon the floor of a hall, or outdoors upon a lawn or the like.

Various modifications may be made within the scope of the claims without departing from the nature of my invention.

10 I claim:

1. A game marker comprising a suitably shaped member having an aperture, and means in said aperture adapted to accommodate a lifting implement whereby said marker may be manipulated in the playing of the game for which it is intended, said aperture and means being of such a character as to permit one marker to be placed upon another in surface engagement therewith and to permit the lifting implement to be readily connected with and disconnected from said means without requiring any force to bring about such connection and separation.
2. A game marker comprising a suitably shaped member having an aperture, and a loop connected with said member and extending diametrically across said aperture

for accommodating a lifting implement, the aperture and said loop being so arranged as to permit one marker to be superimposed upon another in surface engagement therewith.

3. A game marker comprising a suitably shaped member having an aperture, and a loop connected with said member and extending diametrically across said aperture, said loop projecting through and beyond said aperture and converging toward an apex adapted to accommodate a lifting implement, whereby one marker may be superimposed upon another in surface engagement therewith.

4. A game marker comprising a suitably shaped member and means adapted to accommodate a lifting implement whereby said marker may be manipulated in the playing of the game for which it is intended, said means being of such a character as to permit one marker to be stacked upon the other in surface engagement and so that the means of the lowermost marker is accessible to the lifting implement.

In testimony whereof I have hereunto set my hand.

HARRY LATZ.
